UNITED STATES PATENT OFFICE

CHARLES F. McCUALEY AND FRED A. WEAVER, OF DETROIT, MICHIGAN

PACKING TABLE

Application filed May 21, 1927. Serial No. 193,223.

Our invention relates to a new and useful improvement in a packing table adapted for use in packing articles of various kinds and wrapping packages thereon.

5 It is an object of the invention to provide a packing table of this class which will be simple in structure, economical of manufacture, highly efficient in use, light, easily moved from place to place, and one which 10 will be fireproof.

Another object of the invention is the provision of a packing table of this class which will combine various devices so as to make it efficient in use and reduce the labor cost in 15 packing to a minimum.

Another object of the invention is the provision of a table which, on account of its arrangement, may be utilized in a minimum amount of space.

20 Another object of the invention is the provision of a packing table which may be easily and quickly cleaned and one which affords but little surface for adhering of dust thereto.

25 Another object of the invention is the provision of a packing table which may be made on a production basis, the various parts of the various tables being standardized and a table which is so constructed and arranged 30 that it may be knocked down for shipment and easily and quickly assembled at its destination.

Other objects will appear hereinafter.

The invention consists in the combination 35 and arrangement of parts hereinafter described and claimed.

The invention will be best understood by a reference to the accompanying drawings which form a part of this specification, and 40 in which,

Fig. 1 is a front elevational view of the invention.

Fig. 2 is a side elevational view of the invention with parts broken away and parts shown in section.

Fig. 3 is a fragmentary perspective view of one of the corners of the invention.

Fig. 4 is a view taken on substantially line 45 4—4 of Fig. 2.

Fig. 5 is a fragmentary sectional view taken on the line 5—5 of Fig. 2.

Fig. 6 is a view taken on substantially line 6—6 of Fig. 2.

In the invention we provide front standards 9 and rear standards 10 made preferably from angle iron, the rear standards projecting above the upper end of the forward standards 9. Connecting the rear standards 10 and extending to substantially the same height as the forward standards 9 is a rear wall 11. Side walls 12 and 13 connect the rear standards 10 with the forward standards 9. Mounted upon the standards, adjacent the lower end are retaining clips 14 which serve to engage the downwardly projecting flange 15 on the pan or floor-forming member 16. Mounted on the upper end of the forward standards 9 and extending rearwardly to the rear standards 10 is a table top 17 so that there is a compartment provided between the table top 17 and the pan 16. Extending from the forward standards 9 to the rear standards 10 is a U shaped track-forming member 18. Engaging in this track-forming member 18 is a rod 19 upon which is pivotally mounted a closure 20 which serves as a door for the compartment between the pan 16 and the table top 17. Handles 21 are mounted on its closure 20 which is provided with a suitable latch 22. When it is desired to have access to the compartment thus formed, the top 20 may be swung rearwardly in the track 18 as shown in Fig. 3. Projecting diagonally outwardly from each of the standards 10 are braces 23 which, on the opposite standards 10, are in alignment with each other, and provided with a plurality of openings through which rods 24 may be extended, these rods being provided with nuts or other suitable fastening means for retaining the same in position. Extending horizontally from the upper end of the standards 10 are braces 25 which connect to the outer end of the braces 23 and to a cross brace 26. Bearings 27 are mounted on the brace 25 to form a support for the rod 28, upon which may be mounted the spools 29 and 30, the number of these spools and their relative position upon the rod 28 being determined at will. The

55 60 65 70 75 80 85 90 95 100

10 15 20 25 30 35 40 45 50 55 60 65 70 75 80 85 90 95 100

spools are loosely positioned on the rod 28 and a collar 31, secured by a set screw 32 in fixed relation to the rod 28, is provided. The rods 24 are used for the reception of quires of paper and being in spaced relation and at different elevations on account of the incline of the brace 23, the paper may be easily and quickly removed from the various quires, access to the individual quires being an easy matter. The track-forming member 18 is bolted to the standards 9 and to the standards 10 and these various parts are as shown secured together in a manner which would permit their easy assembly and disassembly, the 15 side walls also being bolted to the frame formed by the various standards. The table is preferably made from metal so that it is a fireproof structure, and one which, at the same time, may be easily and quickly cleaned.

It is believed apparent that the various objects set out in the specification are embodied in the invention.

The use of the invention has proven most 25 efficient in operation, particularly in economizing space and the saving of labor.

While we have illustrated and described the preferred form of our invention, we do not wish to limit ourselves to the precise details of structure shown, but desire to avail ourselves of such variations and modifications as come within the scope of the appended claims.

Having thus described our invention what 35 we claim as new and desire to secure by Letters Patent is:

1. In a packing table of the class described having a table top: supports projecting upwardly from said top adjacent the rear edge thereof in spaced relation to each other; horizontally disposed members secured at one end to the upper end of said supports and extending forwardly of said top; means for connecting the free end of said members; braces connecting the free ends of said members to said supports intermediate their ends, each of said braces having a plurality of openings in alignment with openings formed in the other of said braces; and rods projected through 50 said aligned openings.

2. In a packing table of the class described having a top; spaced supports projecting upwardly from the rear of said top; horizontally disposed bars connected at one end to the 55 upper end of said supports and lying in parallel relation; means for connecting the free ends of said bars to said supports intermediate the ends thereof; a bearing mounted on the upper surface of each of said bars; and a rod loosely positioned in said bearings.

3. In a packing table of the class described having a top; spaced supports projecting upwardly from the rear of said top; horizontally disposed bars connected at one end to the 65 upper end of said supports and lying in par-

allel relation; means for connecting the free ends of said bars to said supports intermediate the ends thereof; a bearing mounted on the upper surface of each of said bars; and a rod loosely positioned in said bearings; and 70 spools loosely positioned on said rod; and collars mounted on said rod in fixed relation at opposite ends of said spools and preventing axial movement of said spools on said rod.

In testimony whereof we have signed the 75 foregoing specification.

CHARLES F. McCUALEY.
FRED A. WEAVER.
